SPEAKING TUBE HANDLE FOR
PHONOGRAPHS

Leland D. Norton and Joseph M. Lucarelle,
Bridgeport, Conn., assignors to Dictaphone
Corporation, New York, N. Y., a corporation of
New York

Application March 4, 1941, Serial No. 381,610

6 Claims. (Cl. 74—503)

This invention relates to speaking-tube handles for phonographs, and more particularly to handles which also serve as mounts for phonograph control mechanisms.

It has long been the practice to provide those commercial phonographs known as "dictating machines" with control units mounted upon the speaking-tube handle in such manner as to facilitate manipulation by the machine operator as he holds the speaking tube mouthpiece to his lips while dictating, or to his ear while "listening back" to matter previously recorded.

Control units of this nature generally comprise a control button operatively associated with means for transmitting a starting or stopping impulse to the driving mechanism of the phonograph. The transmission may be accomplished mechanically, electrically, or pneumatically. In one known form, the control unit is cooperative with a Bowden-wire element and is mounted within the speaking tube handle in the manner disclosed in U. S. Patent 1,620,230, wherein the control button has a stem slidably guided in a tube extending into the handle and secured thereto in a fixed position. At its inner end the stem engages one arm of a bell-crank lever pivotally mounted in a block secured within the handle in predetermined relation to the button stem guide by means of screws passing through one side of the handle. An arm of the bell-crank engages the end of a Bowden-wire terminal slidably mounted in the said block. The handle comprises a metallic tubular member of cylindrical form provided at one end with a socket for the reception of a mouthpiece, and at the other end with means for attaching the handle of the speaking tube to the dictating machine. Such a control unit is difficult of assembly in relation to the handle, since there is no positive means within the handle for determining the exact position at which the block must be set to bring the bell-crank lever into operative relation with the push button, and at the same time bring the screw holes in the block into registry with the holes in the handle.

An object of the present invention is to provide a mouthpiece handle for a phonograph speaking-tube having integral means cooperative with the control unit to facilitate their mutual assembly.

A further object is to provide a unitary handle of the character described, made of molded plastic material.

Other objects will be in part obvious and in part described hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which is shown one of the various possible embodiments of the invention,

10 Fig. 1 is a longitudinal cross-section of a speaking-tube handle showing one form of the invention;

Fig. 2 is a cross-sectional view taken on line 2—2 of Fig. 1; and

15 Fig. 3 is a perspective view of the end of the mouthpiece which forms a swivel joint with the handle.

Similar reference characters refer to similar parts throughout the various views of the drawing.

20 In the construction shown, 10 is the speaking-tube, which at one end (not shown) is operatively connected to the dictating machine, and is connected at the other or outer end to a handle member 12, as by means of the threaded connection 14. The handle 12, which is preferably made by molding a thermo-setting plastic material, has the general conformation of a tube tapering gradually from its outer to its inner end 25 where it is internally threaded to receive the externally threaded end of the speaking tube 10. A lock-nut 16 determines the extent to which the tube end enters the handle, and this provides for variable adjustment of these parts.

30 The mouthpiece 20 is also a molded plastic tubular member which tapers hornlike, preferably according to exponential principles, from a relatively large mouth 22 down to a cylindrical neck 24 forming, with a socket portion 26 of the handle, a swivel joint, whereby the mouthpiece 35 may be turned about the axis of the handle. To hold the neck of the mouthpiece to the end of the handle, a self-locking detent is provided which may comprise a split spring ring 28 adapted

40 to interfit within opposing circumferential grooves 30 and 32 formed in the respective members. Such a construction is disclosed in U. S. Patent 1,630,367.

45 The control unit comprises a block 34 anchored within the tubular handle 12 as by means of screws 36 passing through suitable holes 38 in the side of said handle, an actuator 40, and a bell-crank lever 42. The terminal 44 of the outer element of a Bowden-wire 18 is rigidly secured within a bore 46 extending longitudinally

through the block by means of a threaded socket and gland construction 48. The terminal 50 of the inner element of the Bowden-wire has the form of a plunger reciprocatively held within the bore or cylinder 46. The actuator 44 comprises a plunger 52 slidably disposed within a guide passage 54 and carries a finger button 56 at its outer end.

The guide passage 54 is provided within an upper extension 58 of the block 34, extending obliquely across the interior of the handle, the passage 54 aligning with a corresponding guide passage 60 within a tubular stud 62, threaded in an opening in the wall of the handle 12. When the block 34 is properly secured within the handle 12, the block extension 58 will be coaxially aligned with the stud 62 to permit a tubular portion 64 of the extension to telescope within the socket 66 formed within the stud 62, as shown in Fig. 1.

The block 34 also comprises a base or flange portion 68, slidably yet snugly fitted within a groove or way 10 formed in the inner wall of the tubular handle along a longitudinal line located below and diametrically opposite the threaded opening 12 which receives the stud 62. In flange 68 are provided suitable tapped holes 14 registering with the screw holes 18 in the handle when the block is seated in the groove 10 with its extension 58 in coaxial alignment with the stud hole 12 in the handle.

Opposite the base 68 the block 34 is provided with an upwardly inclined extension 76 bifurcated, as at 78, to receive the bell-crank lever 42 which is pivotally mounted within said extension by means of a pin 80, passing through corresponding holes in the lever and in the walls of said extension. The bell-crank lever has an arm 82 overlying the end of the slideable terminal member 50 of the Bowden-wire, and another arm 84 which extends through a slot 86 which vertically bifurcates the block extension 58. The upper end of the lever arm 84 extends into the guide passage 54 and normally engages the inner end of the actuator plunger 52. The actuator is normally held in the position shown in Fig. 1 by the Bowden-wire which, in a well known manner, is resiliently held in the extended position it occupies in the drawing.

The wall of the speaking-tube handle is preferably externally thickened, as at 88, on the same side of the handle as the position of the stud hole 12. This thickening serves to provide sufficient wall thickness for securely supporting said stud, and, below the stud, provides a rib oppositely disposed with respect to a hooklike extension 90 positioned adjacent the upper end of the handle. This hook may serve to support the handle upon a suitable support when the machine is not in use, and, with the said rib, aids in conveniently fitting the handle to the hand of the operator when the mouthpiece is being used.

In assembling, the horn or mouthpiece being removed, the Bowden-wire is first led through the handle and securely fastened to the block 34. The latter is then slipped into the upper or larger end of the handle, and the flange 68 slid downwardly in the groove 10 until the end of the extension 76 engages the opposite wall of the handle. The inner taper of the handle walls, including the wall 92 of the groove 10, is so proportioned in relation to the dimension across the block 34 from the outside of the flange 68 to the end of the extension 76, as to stop further sliding

movement of the block within the handle, when the position has been reached at which the screw holes 14 align with the screw holes 18, and the guide extension 58 is in coaxial alignment with the stud opening 12. The proper assembling of the stud 62 and the actuator 40 having been previously made, it is only necessary to screw the stud into interfitting adjustment with the block extension 58 to complete the assembly of the control unit. After placing the mouth-piece upon the handle, the speaking tube and control mechanism will be ready for use, it being understood that the other ends of the Bowden-wire and speaking-tube have previously been properly attached to the dictating machine.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

We claim:

1. In a dictating machine, in combination, a speaking-tube handle suitable for connection at one end with a mouthpiece and at the other end with a speaking-tube and having a sound passage therethrough from end to end, an actuator mounted in a wall of said handle comprising a member movable in a predetermined path crossing said sound passage, an impulse transmitting control unit introducible into the interior of said sound passage through said one end of the handle and comprising means cooperative with said actuator, means for guiding during assembly said control unit to a fixed operative position in relation to said actuator, and means for rigidly securing said control unit in said position.

2. In a dictating machine, in combination, a speaking-tube handle suitable for connection at one end with a mouthpiece and at the other end with a speaking-tube and having a sound passage therethrough from end to end, an actuator mounted in a wall of said handle comprising a member movable in a predetermined path crossing said sound passage, an impulse transmitting control unit introducible into the interior of said sound passage through said one end of the handle and comprising means cooperative with said actuator, means for guiding during assembly said control unit to a fixed operative position in relation to said actuator, means for determining the arrival of said control unit at said fixed position, and means for rigidly securing said control unit in said position.

3. In a dictating machine, in combination, a unitary molded handle arranged for connection at one end with a mouthpiece and at the other end with a speaking-tube and having a sound passage therethrough from end to end, an actuator mounted in a wall of said handle comprising a member movable in a predetermined path crossing said sound passage, an impulse transmitting control unit introducible into the interior of said sound passage through said one end of the handle and comprising means cooperative with said actuator, integral means formed within said handle for guiding said control unit to a fixed operative position in relation to said actuator, and means for rigidly securing said control unit in said position.

4. In a dictating machine, in combination, a unitary molded handle arranged for connection at one end with a mouthpiece and at the other

end with a speaking-tube and having a sound passage therethrough from end to end, an actuator mounted in a wall of said handle comprising a member movable in a predetermined path crossing said sound passage, an impulse transmitting unit introducible into the interior of said passage through said one end of said handle comprising a support and movable means cooperative with said actuator, means formed integrally within said handle comprising a longitudinally extending groove for guiding said unit support to a fixed position in relation to said actuator, and means for holding said unit immovably in said fixed position.

5. In apparatus of the character described, a 15 unitary molded handle of tubular form tapering internally from a socket of one interior diameter at one end of said handle to a threaded area of reduced diameter at the other end of the handle,

10 having adjacent said one end an external hook projecting outwardly and away from said one end, and having between said ends an internal groove of gradually increasing depth in the direction of said other end.

15 6. In apparatus of the character described, a unitary molded handle of tubular form tapering internally from a cylindrical socket of one interior diameter at one end of the handle to a cylindrical socket of reduced diameter at the other end of the handle, having adjacent said one end an extended hook projecting outwardly and away from said one end, and having between said ends an internal groove of gradually increasing depth in the direction of said other end.
